CLAIM

The ornamental design for a belt attached fishing rod holder, as shown and described.

DESCRIPTION

FIG. 1 is a front perspective view a belt attached fishing rod holder, showing my new design;

FIG. 2 is a rear perspective view thereof;

FIG. 3 is a rear elevational view thereof;

FIG. 4 is a front elevational view thereof;

FIG. 5 is a top plan view thereof;

FIG. 6 is a cross-sectional view taken along line 6—6 of FIG. 4; and,

FIG. 7 is a left side elevational view, the right side being a mirror image thereof.
